Primary Examiner — Ian Simmons*Assistant Examiner* — Yolanda Robinson(74) *Attorney, Agent, or Firm* — Fei-hung Yang(57) **CLAIM**

The ornamental design for a “connector,” as shown and described.

DESCRIPTION

FIG. 1 is a perspective view of a “connector” showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the “connector” showing the “connector” in use.

The broken lines shown in FIG. 8 are for the purpose of illustrating environment and form no part of the claimed design. The broken lines shown in FIG. 3 are for portions of the connector that form no part of the claimed design. None of the broken lines form any part of the claimed design.

1 Claim, 5 Drawing Sheets(56)
